FAILURE CIRCUIT FOR COUNTING CHAINS

Milton A. Clement, Rochester, N.Y., assignor to General Dynamics Corporation, Rochester, N.Y., a corporation of Delaware

Application March 5, 1957, Serial No. 644,020

4 Claims. (Cl. 340—248)

This invention relates to counting chains and, more particularly, to a circuit responsive to the failure of a pulse-operated counting chain.

Pulse counting chains are well known in the art, and may consist of a plurality of elements each of which has two discrete operating conditions which may be characterized as an "on" condition, indicative of a count, and an "off" condition. The elements themselves are usually composed of gas discharge devices, vacuum tubes or relays, and are so interconnected that at all times at least one element is in the "on" condition. The switching of a particular element in the chain from an "off" condition to an "on" condition is dependent on two things; namely, that a pulse be applied to this particular element and that the element in the chain immediately preceding this particular element be in an "on" condition.

It will be seen, therefore, that successive elements in the chain are switched "on" in response to successive pulses applied thereto.

Depending upon the specific type of pulse-operated counting chain employed, the switching of a particular element to an "on" condition may or may not be effective in switching some or all of the preceding elements in the chain which are in an "on" condition to an "off" condition.

In addition, a pulse-operated counting chain may be open ended or it may be connected in a ring. In case of an open-ended counting chain, the maximum number of pulses which can be counted is equal to the number of elements in the chain, and in order to start a new cycle, external reset means must be employed. In the case of a ring-connected chain, the first element in the chain is switched from an "off" condition to an "on" condition in response to a pulse being applied thereto and the last element in the counting chain being in an "on" condition.

From the foregoing discussion it will be seen that although pulse-operated counting chains may differ from one another in many particulars, they are all characterized by the fact that they depend for their proper operation upon some one element in the chain being switched from a first discrete operating condition to a second discrete operating condition in response to each pulse applied to the chain. However, if an element is defective it will not be switched when it should in response to a pulse, and the counting chain will fail to operate. Since a pulse-operated counting chain may be utilized in a complex system for controlling the sequence of operation of a plurality of other circuits in the system, it will be seen that an unindicated failure of the counting chain can be disastrous.

This invention contemplates a circuit responsive to a pulse applied to the chain and the failure of an element of the chain to be switched to an "on" condition thereby for indicating such a failure.

It is therefore an object of this invention to provide means for indicating the failure of a pulse-operated counting chain.

2

It is a further object of this invention to provide means, in cooperative relationship with the pulse-operated counting chain comprising a plurality of elements each having a discrete "on" condition and a discrete "off" condition, for indicating the failure of any element of the chain to be switched to an "on" condition during the time interval that a pulse is being applied thereto.

It is a still further object of this invention to provide means, in cooperative relationship with a pulse-operated counting chain comprising a plurality of elements each having a discrete "on" condition and a discrete "off" condition, for giving an alarm and/or stopping the further application of pulses to the chain in response to the failure of any elements of the chain to be switched to an "on" condition during the time interval that a pulse is being applied thereto.

Although the features of the invention which are believed to be novel are set forth with particularity in the appended claims, these and other objects of the invention, as well as its organization and method of operation, can best be understood by reference to the following description taken in conjunction with the accompanying drawing, in which the sole figure illustrates a preferred embodiment of the invention in cooperative relationship with a typical pulse-operated counting chain.

Referring now to the drawing, there is shown a typical pulse-operated counting chain 100 utilizing cold-cathode triodes as elements thereof. Counting chain 100 consists of priming triode 102-O and two or more pulse counting triodes 102-1 to 102-N (only the first and last of which have been shown in the drawing).

Cathode 104-O of priming triode 102-O is connected to a point of reference potential through resistance 106-O, which is by-passed by capacitance 108-O. In a similar manner the cathodes 104-1 to 104-N of counting triodes 102-1 to 102-N, respectively, are connected to the point of reference potential through resistances 106-1 to 106-N, respectively, which are by-passed by capacitances 108-1 to 108-N, respectively.

Cathode 104-O of priming triode 102-O is coupled to control electrode 110-1 of the first counting triode 102-1 through serially connected resistances 112-1 and 114-1. Resistance 112-1 has a high value relative to both resistances 106-1 and 114-1. The control electrode of each succeeding counting triode is coupled to the cathode of the counting triode immediately preceding it in an identical manner, control electrode 110-N of the last counting triode 102-N being connected to the cathode of the next to the last counting triode through serially connected resistances 112-N and 114-N. Pulses from pulse input source 116, which may be controlled or uncontrolled, are applied to the respective junctions of resistances 112-1 to 112-N and 114-1 to 114-N through capacitances 118-1 to 118-N, respectively, as shown. Thus, the input circuits of all the counting triodes in the chain are identical.

Anodes 120-O of priming triode 102-O and anodes 120-1 to 120-N of counting triodes 102-1 to 102-N are connected in parallel to a point of positive potential B+ through resistance 122, as shown.

A voltage divider consisting of serially-connected resistances 124 and 126 is coupled between the point of positive potential and the point of reference potential. The potential appearing at the junction of resistances 124 and 126 is applied to control electrode 110-O of priming triode 102-O through normally-open reset switch 128 and resistance 130. An integrating circuit composed of resistance 132 and capacitance 134 is connected between the junction of reset switch 128 and resistance 130 and the point of reference potential, as shown.

The cathodes 104-O to 104-N, respectively, of each triode of the chain is connected to a respective output

conductor designated "output O" to "output N," respectively. In addition, if it is wished to control the start of pulsing of pulse input source 116, a pulse start conductor is connected between cathode 104-O of priming triode 102-O and pulse input source 116.

In cooperative relationship with counting chain 100 is the failure circuit contemplated by this invention. This failure circuit comprises a cold-cathode triode 136 having a cathode 138, an anode 140 and a control electrode 142. Cathode 138 is connected to the point of reference potential through resistance 144, and anode 140 is connected to the point of positive potential through normally closed switch 146 and current-operated failure indicating means 148. If it is wished to control pulse input source 116 to stop further pulsing in response to the operation of current-operated failure indicating means 148, a pulse stop conductor is connected between current-operated failure indicating means 148 and pulse input source 116. Current-operated failure indicating means 148 may include an alarm responsive to the operation thereof and/or means for placing a signal potential on the pulse stop conductor in response to the operation thereof. This may be accomplished by means of a current-operated relay, for instance.

Pulses from pulse input source 116 are applied to control electrode 142 of triode 136 through serially-connected capacitance 150 and resistances 152 and 154. The junction of resistances 152 and 154 is connected to the point of reference potential through a large resistance 156 shunted by serially-connected capacitance 158 and resistance 160.

In addition, "output 1" to "output N" of counting triodes 102-1 to 102-N are connected to cathode 138 of triode 136 through an input circuit consisting of unidirectional conducting devices 162-1 to 162-N, poled as shown, and resistance 164 and capacitance 166.

A cycle of operation of the counting chain is initiated by momentarily closing reset switch 128. This causes the positive potential at the junction of resistances 124 and 126 of the voltage divider to be applied to control electrode 110-O of priming triode 102-O to effect the firing thereof. The presence of the integrating circuit consisting of resistance 132 and capacitance 134 assures that the firing potential will be applied for a sufficient time to fire priming triode 102-O even if reset switch 128 is reopened very quickly.

The firing of priming triode 102-O provides a conduction path extending from the point of positive potential through resistance 122, the anode and cathode of priming triode 102-O and resistance 106-O to the point of reference potential, and results in a voltage drop across resistance 106-O which places cathode 104-O at some positive potential. This positive potential causes capacitance 108-O to become charged and also positively biases control electrode 110-1 of the first counting triode 102-1 through serially connected resistances 112-1 and 114-1. In addition, the positive potential on cathode 104-O is applied to the "output O" conductor where it may be utilized to condition some other circuit for operation.

If pulse input source 116 is controlled, positive potential is applied thereto over the pulse start conductor to thereby effect the initiation of pulsing by pulse input source 116. Each of the pulses from pulse input source 116 is applied through capacitances 118-1 to 118-N and resistances 114-1 to 114-N, respectively, to control electrodes 110-1 to 110-N of counting triodes 102-1 to 102-N, and is also applied through capacitance 150 and resistances 152 and 154 to control electrode 142 of triode 136.

The amplitude of each of the pulses applied to control electrodes 110-1 to 110-N, respectively, is insufficient, by itself, to fire any of the counting triodes 102-1 to 102-N. However, when the control electrode of a counting triode is positively biased, the sum of the posi-

tive bias and the amplitude of the pulse is sufficient to fire this triode. Therefore, in response to the first pulse, only the first counting triode 102-1 will be fired, since it is the only one having a positive bias applied to its control electrode at this time.

The initiation of conduction through first counting triode 102-1 provides a voltage drop across resistance 122 in addition to that provided by priming triode 102-O, to thereby lower the anode-cathode voltage across priming triode 102-O sufficiently to cause it to extinguish. Since it is the initiation of conduction of first counting triode 102-1 which causes priming triode 102-O to extinguish, it should be understood that there is a short interval of time prior to the extinction of priming triode 102-O when both triodes 102-O and 102-1 are conducting.

The initiation of conduction through first counting triode 101-1 causes cathode 104-1 thereof to rise quite quickly in potential, applying a positive voltage to the "output 1" conductor, where it conditions some second other circuit for operation. The extinction of priming triode 102-O causes the previously described positive potential on the "output O" conductor to decay at a relatively slow rate due to the discharge time constant of capacitance 108-O.

The quick rise in potential on cathode 104-1 also causes a positive pulse to be applied to cathode 138 of triode 136 through unidirectional conducting device 162-1 and capacitance 166, which presents a small impedance to the quick rise.

When first counting triode 102-1 is conducting, the positive potential on its cathode 104-1 positively biases the control electrode of the second counting triode in the chain, so that it will fire in response to the second pulse from pulse input source 116 and cause first counting triode 102-1 to be extinguished, in an identical manner to that previously described. Therefore, each subsequent pulse is effective in firing the next succeeding counting triode and in extinguishing the preceding triode.

In response to the firing of each counting triode, the quick rise in potential on its cathode causes a pulse to be applied to cathode 138 of triode 136 through the unidirectional conducting device individual thereto in the manner previously described. The extinction of the preceding counting triode is of negligible effect so far as triode 136 is concerned, since capacitance 166 presents a large impedance to the relatively slow decay of the positive potential on the cathode of the preceding counting triode.

At any time during the cycle, or at the end of the cycle when the last counting triode 102-N is conducting, a new cycle may be initiated by momentarily closing reset switch 128. This causes priming triode 102-O to fire, in the manner previously described, and the firing thereof is effective in extinguishing that triode in the counting chain which is conducting at this time because of the added voltage drop in resistance 122.

As previously described, each pulse is applied to control electrode 142 of triode 136 through capacitance 150 and resistances 152 and 154. However, due to the time constant provided by capacitances 150 and 158 and resistances 152 and 160, the potential at control electrode 142 does not rise immediately in response to the initiation of a pulse, but rises relatively slowly during the interval of the pulse. The potential on control electrode 142 does, nevertheless, ultimately reach a value which would be sufficient to fire triode 136 if it were not for the previously described pulse applied to cathode 138 of triode 136 in response to the firing of the next triode in the counting chain. Thus, so long as the counting chain is operating properly, triode 136 will not fire.

However, if one of the triodes in the counting chain is defective, so that it does not fire in response to a pulse applied thereto when its control electrode is positively biased by the preceding triode, its cathode will not rise

in potential, and no positive pulse will be applied through the unidirectional conducting device individual thereto and capacitance 166 to cathode 138 of triode 136. In this case, the pulse-derived potential on control electrode 142 of triode 136 will cause it to fire when it rises sufficiently, since there is no counter-balancing pulse applied to cathode 138. The firing of triode 136 renders it conducting and is effective in operating current-operated failure indicating means 148 which, when operated, provides an alarm and/or provides a signal potential on the pulse stop conductor for stopping further pulsing of pulse input source 116. Triode 136 remains conducting and current-operated failure indicating means 148 remains operated until normally closed switch 146 is opened.

While there has been described what is at present considered to be a preferred embodiment of the invention, it will be obvious to those skilled in the art the various changes and modifications which may be made therein without departing from the invention, and it is aimed in the appended claims to cover all such changes and modifications as fall within the true spirit and scope of the invention.

I claim:

1. First means including a pulse-operated counting chain, wherein said chain includes a first terminal adapted to be coupled to a source of pulses of a given amplitude, a plurality of cold-cathode discharge devices each having a cathode, anode, and control electrode, individual second means comprising a first resistance shunted by a first capacitance connecting the cathode of each of said devices to a point of reference potential, a second resistance connected between a point of positive potential and the anodes of all of said devices, third means for momentarily applying a positive potential to said control electrode of the first device of said chain to effect the conduction thereof, individual fourth means connecting the control electrode of each device following said first device to the cathode of the immediately preceding device of the chain to thereby bias each of these control electrodes at the potential of the cathode to which it is connected, fifth means coupled between each fourth means and said first terminal for applying pulses to the control electrodes of each of said devices following said first device, said given amplitude being per se insufficient to cause firing of a device of said chain but when added to the bias provided by a conducting preceding device being sufficient to normally cause firing of that device; and in combination

therewith sixth means for indicating the failure of a device of said chain to be fired by a pulse applied thereto, wherein said sixth means includes a second terminal, a third resistance coupled between said second terminal and said point of reference potential, individual unidirectional conducting means connecting the cathode of the cathode of each device following said first device to said second terminal, each unidirectional conducting means being poled to be conductive when the cathode to which it is connected is at a positive potential, another cold-cathode discharge device having a cathode, anode and control electrode, a fourth resistance connecting said cathode of said other device to said point of reference potential, a second capacitance coupling said cathode of said other device to said second terminal, seventh means including current-operated failure indicating means connecting the anode of said other device to a point of positive potential, and an input circuit for coupling the control electrode of said other device to said first terminal for applying pulses thereto.

2. The combination defined in claim 1, wherein said input circuit includes a first serially-connected resistance and capacitance coupled between said first terminal and said control electrode of said other device, and a second serially-connected resistance and capacitance coupled between said control electrode of said other device and said point of reference potential.

3. The combination defined in claim 1, wherein said first means further includes a controlled source of pulses coupled to said first terminal, and eighth means coupled between said current-operated failure indicating means and said source of pulses to effect the stoppage of said source of pulses in response to the operation of said current-operated failure indicating means.

4. The combination defined in claim 3, wherein said source of pulses is normally unoperated, and wherein said first means further includes ninth means coupled between the cathode of said first device of said chain and said source of pulses for initiating the operation thereof to provide a series of pulses in response to a positive potential being present on the cathode of said first device of said chain.
